WATER CLOSET SEAT AND COVER

James M. Teahen, Detroit, Mich.

Application March 19, 1934, Serial No. 716,413

6 Claims. (Cl. 4—236)

The invention relates to water closet seats and covers therefor and it is one of the objects of the invention to obtain a construction having a stop for both the cover and the seat in open position which is independent of any contact with the tank or any other external surface. The invention is particularly applicable to that type of water closets in which the tank is integral with the bowl and projects but slightly above the same. With this object in view and also the obtaining of various other advantages, the invention consists in the construction as hereinafter set forth.

In the drawing:

Fig. 1 is a plan view of the seat and cover in closed position;

Fig. 2 is a side elevation of a portion of the cover and seat showing the hinge connection therefor;

Fig. 3 is a similar view showing the cover in raised position and with the hinge post partly in section;

Fig. 4 is a similar view showing the cover raised and illustrating the stop for both seat and cover;

Fig. 5 is a rear elevation of one of the hinge posts and its connections.

Heretofore hinge connections for water closet seats and covers have been designed to form a stop for limiting the angular movement. Such stops have, however, been necessarily placed so close to the turning axis that when seat or cover is thrown back the comparatively long lever arm will transmit a high stress to the stop. As a consequence these stops are frequently broken off and are not satisfactory for service. To overcome this difficulty I have designed a construction in which the cover when thrown back is stopped by the seat and the seat when thrown back is stopped by the cover in cooperation with a stop on the hinge post, but of such construction as to relieve the stress from the latter.

As illustrated, A is the seat and B the cover, each of which is provided with a rearwardly extending portion for engaging the hinge fittings. The portion C extending rearward from the seat A is arranged between hinge posts D and is pivotally connected thereto, preferably by a pivot pin E passing completely through the portion C and engaging sockets in the posts. The rearwardly extending portion F of the cover B also extends between the hinge posts and is provided on its opposite sides with L-shaped hinge brackets G. The upper arms of these brackets are secured to the sides of the member F by suitable means such as the wood screws H and the dowel pins I. The downwardly extending arms of the L are aper-

tured to be sleeved upon the rod or pin E intermediate the post D and the member C.

To form a stop for limiting the swinging movement of the cover B the rear end of the extension C on the seat A is so fashioned as to interfere with the portion F of the cover when the latter is swung slightly beyond the vertical. The grain of the wood forming the member C extends in such direction that the rear face is formed by end grain which therefore constitutes a substantially unyielding abutment. Thus as shown the portion C is rounded at C' to provide clearance for the swinging of the cover to the vertical and slightly beyond, while the lower portion C² of the member C is tangent to the curve C' and stands in the path of further swinging movement of the portion F of the cover. Thus without impact upon the hinge post the cover will be arrested in a stable position where it inclines slightly to the rear of the vertical.

It is necessary to also provide a stop for the cover when the seat is raised as well as providing a stop for the seat itself. To accomplish this without overstressing any part I have devised the following construction. The hinge bracket D is formed with a semi-circular segment D' against which the hinge brackets G bear and below this segment the post is cut away to form a shoulder D². The hinge bracket G is provided with a projecting lug G' beneath the shoulder D² but of such dimensions that during the movement of the cover as before described, it will not come in contact with said shoulder. Thus as specifically shown the lug G' is in the form of a segment of substantially 70° and therefore would permit a movement of 110° in turning from a position where it is in contact with the shoulder D² on one side of the axis to a position for contact with said shoulder on the opposite side of the axis.

However, the angular movement permitted to the cover from its closed position to its position where it contacts with the stop portion C² is something less than 110°, as for instance 105°, so that in the opening of the cover the lug G' will not impinge against the shoulder D². If the seat is then lifted this will permit further movement of the cover which will bring the lug G' in contact with the stop shoulder D², but the amount of 5° is so slight as to not produce any objectionable impact. When the seat is completely raised it will come in contact with the cover which will arrest further movement, but the impact of the seat against the cover is cushioned by the resiliency of the materials so that the stress transmitted to the lug G' and stop

shoulder D² is not excessive. Thus the seat forms the stop for the cover and the cover forms the stop for the seat, and in neither case is there any objectionable stress transmitted to the hinge 5 post.

What I claim as my invention is:

1. The combination with a water closet seat and a cover therefor, each provided with a rearwardly extending portion, of hinge posts on opposite sides of said rearwardly extending portion of said seat, a pivot pin extending through said rearwardly extending portion of the seat and engaging said posts, and hinge brackets on said cover also pivoted on said pin and permitting of 10 the swinging of the cover independent of the seat to a position slightly in rear of the vertical, the end of said rearwardly extending portion of the seat being arranged in the path of the rearwardly extending portion of said cover and constituting 15 a stop for preventing further independent swinging movement thereof.

2. The combination with a water closet seat and a cover therefor, each provided with a rearwardly extending portion, of hinge posts on opposite sides of said rearwardly extending portion of said seat, a pivot pin extending through said rearwardly extending portion of the seat and engaging said posts, and hinge brackets on said cover also pivoted on said pin and permitting of 20 the swinging of the cover independent of the seat to a position slightly in rear of the vertical, the end of said rearwardly extending portion of the seat being arranged in the path of the rearwardly extending portion of said cover and constituting 25 a stop for preventing further independent swinging movement thereof, said seat being formed of wood with the grain thereof directed to expose end grain as the stop for the cover.

3. The combination with a water closet seat and a cover therefor, each provided with a rearwardly extending portion, of hinge posts on opposite sides of said rearwardly extending portion of said seat, a pivot pin extending through said rearwardly extending portion of the seat and engaging said posts, hinge brackets on said cover also pivoted on said pin and permitting of the 30 swinging of the cover independent of the seat to a position slightly in rear of the vertical, the end of said rearwardly extending portion of the

seat constituting a stop for preventing further independent swinging movement of said cover, and cooperating stop members on said hinge post and hinge bracket held out of contact when said cover is arrested by said seat but brought into contact upon a slightly further movement of the cover permitted by the lifting of the seat and forming a means for limiting the angular movement of both cover and seat. 5

4. The combination with a water closet seat and a cover therefor, of a hinge connection for said seat and cover including a stationary hinge post and seat and cover engaging members coaxially pivoted thereto permitting independent swinging of the cover, a stop on said seat for 10 limiting said independent swinging movement of the cover, and a stop for said cover on said hinge post engageable by a slightly greater swinging movement permitted by the lifting of the seat and constituting a means for arresting movement 15 of both cover and seat.

5. The combination with a water closet seat and a cover therefor, of hinge posts to which both seat and cover are pivoted, cooperating stops on said cover, and hinge post for limiting the swinging movement of the cover, an additional stop on said seat for limiting the swinging movement of said cover relative thereto to not greater than that permitted by the stop on said post whereby the latter is relieved from at least a portion of the 20 stress when the cover alone is raised. 25

6. In a water closet, the combination with a seat and a cover therefor, said seat being provided with a rearwardly extending portion, of a pivot pin extending transversely through said rearwardly extending portion of the seat, posts engaging the opposite ends of said pivot pin, brackets on said cover also pivotally engaging said pin on opposite sides of said rearwardly extending portion, a segment on said posts and a cooperating segment on said hinge bracket for limiting the angular movement of the latter, and a stop formed by the end of said rearwardly extending portion of the seat for arresting movement of said cover and relieving said cooperating 30 segments from stress, said cooperating segments engaging upon the lifting of said seat and forming a stop for both seat and cover. 35
